UNITED STATES PATENT OFFICE.

JOHN D. MULVEHILL, OF SPOKANE, WASHINGTON.

NON-REFILLABLE BOTTLE.

1,111,082.

Specification of Letters Patent.

Patented Sept. 22, 1914.

Application filed February 19, 1914. Serial No. 819,612.

To all whom it may concern:

Be it known that I, JOHN D. MULVEHILL, a citizen of the United States, residing at Spokane, in the county of Spokane and State 5 of Washington, have invented certain new and useful Improvements in Non-Refillable Bottles, of which the following is a specification.

This invention relates to non-refillable 10 bottles.

One of the objects of the present invention is to provide a simple and practical non-refillable bottle having few parts which will be cheap to manufacture.

15 A further object is to provide a bottle of the above character with parts which may be readily assembled and so arranged as to prevent a refilling of the bottle.

Other objects will be in part obvious and 20 in part hereinafter pointed out.

The invention accordingly consists in the features of construction, combination of elements and arrangements of parts which will be exemplified in the device hereinafter described, and the scope of the application of 25 which will be indicated in the following claim.

In the accompanying drawing wherein is 30 shown one of various possible embodiments of the present invention Figure 1 is a vertical sectional view of the complete device in normal position; Fig. 2 is a sectional perspective view of a valve; Fig. 3 is a perspective view of one of the parts and Fig. 4 is a 35 perspective view of the casing containing the valve.

Similar reference characters denote corresponding parts in the several views.

Referring now to the drawing in detail, 40 and more particularly to Fig. 1, 5 represents the body portion of a bottle having a neck 6 and a depressed portion 7 between the neck and body portion. On top of the neck is positioned a casing 8, shown in detail in Fig.

45 4, comprising a cylindrical body having a central transverse perforated diaphragm 9. Between the casing 8 and the neck of the bottle is interposed a perforated disk 10 of cork, or other suitable material with which 50 co-acts a spherical valve member 11, mounted at the upper end of a stem 12, the lower part of which carries a plurality of radial arms 13 co-acting with the interior of the neck 6 of the bottle, thereby to guide it vertically, 55 in its up and down move.

The upper part of the valve member 11 is

provided with a tapering projection 14 adapted to pass through the hole 15 in the center of a rider or spanner 16. This rider is shown in detail in Fig. 3, and besides being provided with a central opening also has a plurality of upstanding guiding members 17 co-acting with the interior of the casing 8. This spanner in connection with the perforated diaphragm 9 is intended to prevent the insertion of wires or other means to hold the valve in raised position and permit the bottle to be refilled.

In normal position it will be noted that the valve member 11 seats upon the perforated disk 10 and positively closes this valve and prevents a re-filling of the bottle. When, however, the bottle is inverted the valve member 11 will drop under the action of gravity into contact with the hole 15 in the spanner. There is, however, sufficient space between the legs or guiding members 17 of the spanner and the interior wall of the casing to permit a flow of liquid therebetween and through the perforations in the 80 diaphragm, and thence out of the bottle.

The valve casing and parts are held securely in place by means of a cap 18, which is cylindrical in shape, and is intended to fit over the casing and the neck of the bottle. The lower part of this cap is provided with a plurality of legs 19 which enter the depression 7 at the base of the neck of the bottle, and are secured in place by means of cement or the like 20. The upper part of 85 the cap is of course provided with an opening adapted to be closed by a cork 21 in the usual manner. It is thus seen that the cap cannot be removed without breaking the legs 19 embedded in the cement, and as it is impossible to remove this cap it will also be impossible to tamper with the valve and hold it in open position to permit a re-filling of 90 the bottle.

It is thus seen that this invention provides 100 a simple and practical non-refillable bottle, having few parts, which will be cheap to manufacture and easy to assemble. In short the invention is believed to accomplish among others all of the objects and advantages set forth.

As many changes could be made in the above construction and many apparently 110 widely different embodiments of my invention could be made, without departing from the scope thereof, I intend that all matter contained in the above description or shown

in the accompanying drawing shall be interpreted as illustrative and not in a limiting sense.

Having thus described my invention what I claim as new and desire to secure by Letters Patent is:

In a non-refillable bottle having a neck, in combination a disk valve seat of relatively soft material positioned at the top of said neck, a valve casing resting on said valve seat, a gravity actuated valve of generally globular shape within said casing and coacting with said valve seat, a perforated diaphragm in said casing protecting said valve,

a perforated member between the diaphragm and the valve seat for protecting said valve, having a perforation adapted to guide the valve in its movement, and a cap adapted to fit over said casing having a threaded connection with the neck of the bottle and having its lower end permanently secured to the body of the bottle.

In testimony whereof I affix my signature in presence of two witnesses.

JOHN D. MULVEHILL.
